[57] CLAIM

The ornamental design for the ceiling fan blade iron, as shown and described.

DESCRIPTION

FIG. 1 is a bottom view of a ceiling fan blade iron embodying my new design;

FIG. 2 is an end view of the ceiling fan blade iron;

FIG. 3 is another end view of the ceiling fan blade iron;

FIG. 4 is a side view of the ceiling fan blade iron; and,

FIG. 5 is a perspective view of the ceiling fan blade iron; the broken lines showing a fan blade are for illustrative purposes only and form no part of the claimed design.
